CONTROL PANEL FOR A COMBINED CLOCK AND TIMER

Paul T. Flumm, Oakville, and Vernon B. Harris, Waterbury, Conn., assignors to Robertshaw Controls Company, Richmond, Va.

Filed Apr. 30, 1974, Ser. No. 465,482

Term of patent 14 years

Int. Cl. D10—01

U.S. Cl. D10—2

FIG. 1

FIG. 2

FIG. 3

FIG. 1 is a front view of a control panel for a combined clock and timer showing our new design;

FIG. 2 is a top plan view thereof, the bottom plan view being identical thereto; and

FIG. 3 is a left side view thereof, the right side being a mirror image thereof.

We claim:

The ornamental design for a control panel for a combined clock and timer, substantially as shown and described.
